HAROLD P. HASTINGS, OF SYRACUSE, NEW YORK, ASSIGNOR TO CROUSE-HINDS COMPANY, OF SYRACUSE, NEW YORK, A CORPORATION OF NEW YORK.

ELECTRIC SWITCH.

1,307,006.

Specification of Letters Patent. Patented June 17, 1918.

Application filed September 19, 1914. Serial No. 862,500.

To all whom it may concern:

Be it known that I, HAROLD P. HASTINGS, a citizen of the United States, and a resident of Syracuse, in the county of Onondaga and State of New York, have invented a certain new and useful Electric Switch, of which the following is a specification.

This invention has for its object an electric switch which is particularly simple in construction and highly efficient in use; and it consists in the novel features of construction hereinafter set forth and claimed.

In describing this invention, reference is had to the accompanying drawings in which like characters designate corresponding parts in all the views.

Figure 1 is a sectional view, partly in elevation, of a switch embodying my invention, the same being shown as mounted on 20 a panel-board, which is shown as broken away.

Fig. 2 is a plan of parts seen in Fig. 1, the cap being shown in section.

Fig. 3 is a plan view of the base, parts 25 being removed with the exception of one of the pairs of terminals.

Fig. 4 is a horizontal sectional view taken on line 4—4, Fig. 3, the switch arm being included; and

Fig. 5 is a detail view illustrating the switch mechanism in elevation.

This electric switch comprises, generally, a base, switch mechanism mounted on the base, and a cap inclosing said mechanism 35 and the base and having a wall skirting the sides of the base.

1 designates the base which is square in plan and formed with a recess open at its top and one side, this recess being formed 40 by opposing uprights 2 rising from the base, and a wall 3 between the uprights. The wall 3 forms one of the sides of the base and the side edges of the uprights farthest removed from the wall 3 are located some distance in, from the side of 45 the base 1 opposite to that side on which the wall 3 is located.

The switch mechanism is supported by a frame extending into the recess, that is, 50 between the uprights 2. The frame includes upright legs 4 and a cross-piece or bridge 5 connecting the legs, the legs having turned feet 6 at their lower ends. The frame is arranged with one of the legs 4 located near the rear wall 3, and with the

other leg outside of the recess formed by the uprights 2 and wall 3. The feet 6 rest on raised projections 7 on the base 1.

The switch mechanism is supported by plates 8 depending from the cross-piece and includes movable switch arms 9, and push buttons 10 for operating the switch arms 9, the push buttons extending through the cross-piece 5. The switch mechanism may be of any desirable form, size and construction, and *per se*, forms no part of this invention.

The switch arms coact with pairs of terminals supported by the base, the members 11 and 12 of each pair being mounted, 70 respectively, on the base at the lower ends of the uprights 2, and on the uprights 2, and preferably on the upper ends of said uprights. Each terminal 11 or 12, is angular in form, and has a lateral extension 75 or arm 13 or 14, the extension 13 of the terminal 11 supporting switch contacts 15 and the extension 14 of the terminal 12 supporting contacts 16, the contacts 15 and 16, being located between the planes of opposing faces of the uprights 2 and the contacts 15 being located outside of the recess formed by said uprights 2 and the wall 3. The arms 13 on the terminals 11 are turned downwardly, as at 17, into depressions 18 80 formed in the base 1 on opposite sides of one projection 7, and the arms 14 of the terminals 12 are formed with upturned ends 19 which support the contacts 16. The terminals are held in position by suitable 85 screws, as 20, extending into the base from the lower side thereof; and electrical connection is made between the terminals and the bus-bars 21 on the panel-board 22 on which the base is mounted, by means of 90 screws 23, 24, extending through the terminals 11 and 12 from the front side of the base 1 through the underlying portions of the base and uprights 2 and into said bus-bars. These screws serve not only to make 95 the electrical connection with the bus-bars, but also to secure the base 1 in position. The base 1 is formed with suitable barriers 26 on its bottom, which barriers are located between the bus-bars.

27 is the cap which is shaped to entirely inclose the base 1 and mechanism supported thereby, and also the open sides of the recess of the base, the side walls of the cap skirting the sides of the base and be- 100 105 110

ing provided with notches 28 in their lower edges through which the bus-bars pass. The top of the cap is provided with suitable openings through which the push buttons 5 10 extend; and the cap is held in position by any suitable means, as screws 29, extending therethrough and into laterally extending ears 30 on the cross-piece, or bridge 5.

This switch is particularly advantageous 10 in that it is economical in manufacture, and in that owing to the formation of its base, the parts of the switch mechanism are readily accessible upon the removal of the cap.

What I claim is:

- 15 1. An electric switch comprising a base formed with uprights rising therefrom, pairs of terminals each including a member mounted on the base at the lower end of one of the uprights and a member mounted on 20 the upper end of one of the uprights, mechanism supported by the base and extending between the uprights and having means co-acting with the pairs of terminals, and means for securing the base in position including fastening screws extending through 25 the terminals and the underlying portions of the base and the uprights thereof, substantially as and for the purpose set forth.
2. An electric switch comprising a base 30 formed with a recess open at its top and one side, and switch mechanism mounted on the base including a frame having legs rising from the base, one leg being located in the

recess near the rear wall thereof and the other being located out of the recess, and a 35 cross-piece connecting the upper ends of the legs, and mechanism supported by the cross-piece, substantially as and for the purpose specified.

3. An electric switch comprising a base 40 formed with opposing uprights rising therefrom, and mechanism mounted on the base comprising a frame having legs rising from the base, one leg being located between the uprights, and a cross-piece connecting the 45 upper ends of the uprights, pairs of terminals mounted on the base on opposite sides of the frame, one member of each pair being located at the lower end of one of the uprights and at one side of one of the 50 legs of the frame and the other terminal being mounted on one of the uprights, and mechanism depending from the cross-piece and including movable arms for coacting with the pairs of terminals, substantially as 55 and for the purpose set forth.

In testimony whereof, I have hereunto signed my name in the presence of two attesting witnesses, at Syracuse, in the county of Onondaga, and State of New York, this 60 25th day of August, 1914.

HAROLD P. HASTINGS.
